REPLACEABLE ELEMENT TR TUBE

Ferdinand A. Lesch, Beverly, Mass., assignor to Bomac Laboratories Inc., Beverly, Mass., a corporation of Massachusetts

Application November 26, 1956, Serial No. 624,431

7 Claims. (Cl. 315—39)

The present invention relates broadly to gaseous discharge ultra high frequency switching devices and more specifically to a novel structure incorporating both the capacitive and inductive elements in a unitary device adapted to be mounted in rectangular waveguide to form together with an encapsulated window a complete transmit-receive tube.

The embodiment of the invention is commonly employed in microwave radar systems to protect the receiver by means of a highly attenuating gaseous discharge within a waveguide structure when the transmitter is pulsing. During the receive cycle the signal energy will be permitted to pass to the receiver unattenuated. Examples of prior art transmit-receive or TR devices incorporating the capacitive cone structure defining a discharge gap and inductive metallic members are illustrated in the text "Microwave Duplexers" by L. D. Smullin and C. G. Montgomery, McGraw-Hill Book Co., New York, 1948, pages 67-70 and 106-112. With the structure therein described contained within a hermetically sealed envelope such prior art devices are commonly filled with an ionizable atmosphere under reduced pressure. It is in the selection of this atmosphere that prior art transmit-receive tubes involve a series of compromises in the desirable electrical parameters such as spike leakage energy, flat leakage power, recovery time and arc loss.

Ionizable gases such as hydrogen or argon generally are combined with a small amount of water vapor to enhance the electron capturing properties of the gas in order to improve recovery time. However, this gas filling increases the leakage power and arc loss values. In addition, certain mechanical disadvantages result from oxidation of the internal metallic components or corrosion of the hermetically sealed joints of the overall waveguide envelope. A further disadvantage exists in that with prior art construction, certain light-weight metals such as aluminum cannot be employed for the waveguide assembly because of the large variance in the coefficient of expansion of such metals and the dielectric materials used for the window seals.

The primary object of the present invention, therefore, is to provide a novel transmit-receive tube in which each resonant element is provided with its own internal gas fill selected for the optimum electrical characteristics.

A further object is to provide a novel transmit-receive tube with separable and interchangeable resonant elements which are replaceable individually without necessitating replacement of the entire tube with an accompanying saving in costs.

A still further object is to provide individual replaceable TR cells each possessing the inductive and capacitive components of a complete resonant circuit together with an encapsulated structure to permit the use of separate gas fillings.

Another object is to provide individual replaceable resonant elements to form collectively a TR tube in which each element contains its own gas filling enclosed within a dielectric enclosure to eliminate the disadvantages of

2

prior art devices wherein the gas filling is enclosed within a metallic enclosure.

These and other objects are attained in the illustrative embodiment of a multi-element broadband TR tube by means of individual encapsulated components mounted in a section of hollow pipe rectangular waveguide. The first important resonant element is the input window which is provided with a frame member defining a dielectric enclosed aperture of conventional construction. 10 A trough member of a dielectric material is mounted on one side to completely encapsulate this structure and provide an enclosure containing a gaseous atmosphere selected to optimize the recovery time and arc loss characteristics. Spaced within the waveguide section at the 15 conventional quarter-wavelength distance are individual integral resonant cell assemblies constructed in accordance with the teachings of the present invention. Each cell includes capacitive electrode members enclosed within a dielectric envelope with inductive elements disposed 20 coaxially on either side of this encapsulated structure. The top and bottom members of the complete assembly are designed to make good electric contact when mounted in the waveguide section. Clamping means engage the top member to retain the assembly in operative position. The 25 individual cells are provided with a gas fill within the enclosure, however, in this instance such parameters as spike leakage energy and flat leakage power are of primary concern and water vapor may be eliminated. Each cell may further be provided with an igniter electrode 30 structure of well known construction. Although only one of the cells need be connected to a suitable direct current source to facilitate partial ionization of the gas, the provision of the igniter electrode in all cells permits interchangeability or replacement during operation without 35 the removal of the overall waveguide assembly from the system. Furthermore, the igniter top cap provides a convenient means for handling of the individual cells during the mounting operation.

In usage the need for maintenance of large inventories 40 of prior art tubes is eliminated since only the individual cells need be stocked. This will result in virtual elimination of lost or down time in demounting of complete tube assemblies as well as considerable savings in replacement costs.

Other objects, advantages and features will be evident 45 after consideration of the following detailed specification and the appended drawings, in which:

Fig. 1 is a perspective view of the illustrative embodiment showing one of the replaceable cells in position for mounting;

Fig. 2 is an enlarged side view of the embodiment with the resonant window in perspective and a portion of the waveguide removed to reveal the mounted resonant cell assembly;

Fig. 3 is an enlarged cross-sectional view of the resonant input window assembly; and

Fig. 4 is an enlarged cross-sectional view of the replaceable cell assembly of the embodiment.

Referring now to Figs. 1 and 2, the illustrative embodiment of a complete broadband TR tube incorporating all demountable elements is shown and comprises a section of hollow pipe waveguide 1 with mounting flanges 2 and 3 sealed at the ends thereof. The resonant input window assembly shown generally at 4 may be simply mounted at one end by screw fastening means secured 60 to the narrow side of the window assembly with the ends of the fastening means shown at 5. Threaded apertures 6 of the assembly mate with similar apertures in the flange 2 along the broadside to facilitate mounting of the overall tube in a waveguide system.

The demountable resonant cell assembly 7 is shown 65 in position for mounting in the waveguide 1 by means

of a threaded clamping base 8 secured to the top wall of the waveguide. A contact sleeve 9 is secured to the opposite wall of the waveguide 1 to receive the lower portions of the cell assembly. To assure accurate positioning of the cell without any subsequent rotation, a key 10 is provided in sleeve 9 with a groove 11 in the cell bottom. After the cell has been inserted a teflon washer 12 and metal ring 13 are positioned within base 8 and a clamping ring 14 retains the cell in position.

Turning now to Fig. 2 the output end of the tube will be seen. According to the teachings of the invention it will no longer be necessary to evacuate and fill the overall waveguide 1 and, therefore, a flat metallic plate 15 is sealed within flange 3. A resonant aperture 16 is centrally provided within plate 15 and the conventional hermetically sealed dielectric enclosure may be omitted.

One of the features of the present invention resides in the use of light weight metals since critical glass-to-metal seals necessary in the prior art to provide a vacuum tight tube have been eliminated. It is, therefore, desirable to fabricate flanges 2 and 3, waveguide 1 and metallic plate 15 from aluminum stock such as 61S-T6 instead of the conventional brass and steel found in prior art tubes.

The resonant encapsulated window assembly 4 will now be described in detail by referring to Fig. 3. A relatively short section of waveguide 17 has brazed thereto a flange 18 which will mate with flange 2 of the tube assembly. Metal plate 19 is secured to section 17 and is provided with a resonant iris covered with a dielectric enclosure 20 of the conventional construction. The inner surface of plate 19 is heavily glazed in the area indicated at 21 with a beaded powdered glass suspension and a glass trough 22 formed from glass tubing is heat sealed to this glazed side. Trough 22 is provided with an exhaust stem 23 through which the complete encapsulated assembly may be evacuated and filled with the desired gaseous atmosphere. In an illustrative embodiment a filling of 30 millimeters of argon was employed with a relatively small percentage of water vapor added to enhance the recovery time characteristics. If desired, quartz wool may also be positioned within the glass trough in the manner well known in the art.

The complete window assembly may then be provided with a wire mesh gasket 24 to provide for good electrical contact when the tube is mounted in waveguide structure.

The demountable resonant cell assembly 7 is shown in detail in Fig. 4 and comprises a top cylindrical member 25 having a hub portion 26 and a flanged portion 27. A thin disc collar 28 of a highly conductive metal such as copper is secured to the flange 27. A lower cylindrical member 29 is axially disposed from member 25 and comprises a flange 30, a portion 31 of reduced cross section, and a still narrower section 32 terminating in a substantially conical point 32A to define one of the gap electrodes. A passageway 33 extends axially through this member with apertures 34 provided in the walls of portion 32 to facilitate evacuation of the complete cell assembly. A glass cylinder 35 is hermetically sealed at its ends to hub portion 26 and portion 31 of member 29 to define a gas tight envelope.

To complete the gap electrode structure of the capacitive resonant circuit of the overall cell a combined screw type electrode with an igniter electrode is provided according to the teachings of U. S. Patent No. 2,524,268 issued October 3, 1950 to Henry J. McCarthy. In the embodiment a hollow conical tip screw 36 with an open end is threaded into the hub portion 26 until the desired spacing from tip 32A is achieved to tune the cell assembly to a predetermined resonant frequency. Nut 37 and washer 38 lock the screw in the tuned position. An igniter electrode 39 of standard construction is positioned within screw 36 and is supported by means of collar 40 and glass bead 41. Top cap 42 provides means for connec-

tion to a direct current voltage supply. Spacer 43 is secured to member 25 to support the igniter electrode collar 40. The inductive components of the resonant circuit of the overall cell assembly comprise a pair of rod members 44 and 45 supported between flanges 27 and 30 and securely fastened therein. The provision of these inductive members as a part of the demountable cell assembly eliminate the need for the conventional flat metallic plate structures generally found in TR devices.

10 A multi-fingered resilient contact ring 46 is secured to member 29 to provide for positive engagement of the overall cell assembly within sleeve 9 when the assembly is inserted in the waveguide 1. Exhaust tube 47 is also secured within the hollow portion of member 29 in alignment with passage 33 to provide for evacuation of the cell envelope. An appropriate gaseous atmosphere may then be introduced into the cell. Since the electrical considerations for this component of the overall tube are primarily spike leakage energy and flat leakage power, a different gas fill may be employed from that of the encapsulated window. In this embodiment approximately four and one half millimeters of argon and one millimeter of hydrogen was found to yield the most satisfactory results. After filling, the exhaust tubulation may be tipped-off, sealed and a protector cover 48 inserted as shown.

15 The complete tube assembly comprising one or more of the resonant cell assemblies and an encapsulated input window each having its own integral gas fill provides a unique device over prior art tubes in that replacement of individual components may be easily accomplished. This results in cost savings since under prior art design 20 the complete tube including expensive metal envelopes must be replaced when electrical characteristics exceed or fall below one or more of the specified requirements. A further advantage resides in the fact that cell assemblies 25 may be replaced without disturbing the waveguide system set up.

20 With the structure disclosed the problem of metallic sputtering under fired conditions of intense ionization is considerably reduced since all gaseous discharges are confined within dielectric enclosures. As a result it is now possible to use combinations of metals and gases which 25 were heretofore noncompatible. Aluminum is therefore desirable for all metallic components not requiring a high coefficient of expansion to match that of glass. This light weight metal aids in reducing the overall system weight which is particularly desirable in airborne radar systems.

30 While a specific illustrative embodiment has been described it will be evident to skilled artisans that various modifications may be incorporated. An example may be the provision of a tuning mechanism within the cell assembly in place of the fixed tuned structure disclosed in the 35 specification.

What is claimed is:

1. An ultra high frequency gaseous discharge switching device comprising a metallic waveguide envelope, a demountable encapsulated resonant window assembly 60 disposed at one end of said waveguide envelope with an apertured plate member sealed at the opposite end thereof, a unitary demountable composite resonant circuit member spaced at intervals of approximately one-quarter of a wavelength within said waveguide envelope, said resonant circuit member including both the capacitive and inductive elements with the capacitive elements enclosed within a dielectric envelope and an individual filling of a gaseous atmosphere contained within said window assembly and dielectric envelope.
- 65 2. An ultra high frequency gaseous discharge switching device comprising a section of metallic rectangular waveguide, a demountable encapsulated resonant window assembly positioned at one end of said waveguide section, a metallic plate member having a central resonant aperture secured at the opposite end thereof, a demount-

able resonant cell assembly spaced at intervals of approximately one-quarter of a wavelength within said waveguide section, said cell assembly including capacitive discharge gap electrode structure enclosed within a dielectric envelope and inductive elements positioned parallel to said capacitive electrode structure and an individual filling of a gaseous atmosphere contained within said window assembly and dielectric envelope.

3. An ultra high frequency gaseous discharge switching device comprising a section of hollow rectangular waveguide, a demountable encapsulated resonant window assembly positioned at one end of said waveguide section, a metallic plate member having a central resonant aperture secured at the opposite end thereof, a demountable resonant cell assembly spaced at intervals of approximately one-quarter of a wavelength within said waveguide section, said resonant cell assembly comprising an upper and lower member with metallic inductive members supported therebetween, said upper and lower members each defining a capacitive electrode with said electrodes being in axial alignment and spaced apart to provide a discharge gap, a dielectric envelope enclosing said capacitive discharge gap electrodes and a filling of a gaseous atmosphere contained within said dielectric envelope.

4. An ultra high frequency gaseous discharge device comprising a section of hollow rectangular waveguide, a demountable gas-filled encapsulated resonant window assembly positioned at one end of said waveguide section, a metallic plate member having a central resonant aperture secured at the opposite end thereof, a demountable resonant cell assembly spaced at intervals of approximately one-quarter of a wavelength within said waveguide section, said resonant cell assembly comprising an upper and lower member each supporting a substantially conical electrode with said electrodes being in axial alignment and oppositely disposed to define a discharge gap, a cylindrical dielectric member hermetically sealed to said upper end lower member to thereby encapsulate said discharge gap in a vacuum tight enclosure and filling of a gaseous atmosphere contained within said enclosure, a flanged portion provided on each of said upper and lower members and a pair of metallic members secured to and extending between said flanged portions.

5. An ultra high frequency gaseous discharge switching device comprising a section of hollow rectangular waveguide having a plurality of spaced aligned apertures disposed in the upper and lower broad walls along the longitudinal axis thereof, a demountable gas-filled encapsulated resonant window assembly positioned at one end of said waveguide section, a metallic plate member having a central resonant aperture secured at the opposite end thereof, a demountable gas-filled resonant cell assembly mounted in said waveguide section and extend-

ing between each pair of aligned waveguide apertures, said resonant cell assembly having means for engaging the walls of said apertures to thereby provide good electrical contact, said cell assembly further providing in a unitary structure the capacitive and inductive elements of a composite resonant circuit when mounted in the waveguide section.

6. A transmit-receive tube comprising a section of rectangular waveguide having positioned therein a plurality of unitary resonant cell assemblies adapted to be interchanged with one another or removed for replacement, each of said cell assemblies comprising a top cylindrical member having a flanged section and a central axial passageway, a threaded conical tipped metallic member extending through said axial passageway, a bottom cylindrical member having a flanged section and a central portion of reduced cross-section terminating in a substantially conical tip, metallic posts secured to said flanged sections to thereby maintain said top and bottom members in spaced relationship with said conical tips being oppositely disposed to define therebetween a capacitive discharge gap, dielectric enclosure means joined to said top and bottom members to enclose said discharge gap and a filling of an ionizable atmosphere contained within said enclosure, a demountable gas-filled encapsulated resonant window assembly enclosing one end of said waveguide section and a flat metallic member with a central resonant aperture hermetically sealed to the opposite end of said waveguide section.

7. A transmit-receive tube comprising a section of rectangular waveguide of a lightweight metal having positioned therein a plurality of demountable resonant cell assemblies, each of said cell assemblies comprising an upper and lower flanged member connected together by a pair of cylindrical posts joined thereto near the peripheral edge of the flanges, capacitive discharge gap electrode structure oppositely disposed from and supported by said upper and lower members, a dielectric envelope enclosing said electrode structure and a filling of an inert gaseous atmosphere contained therein, an encapsulated resonant window assembly containing a gaseous atmosphere and water vapor removably secured to one end of the waveguide section and a plate member having a central resonant opening permanently secured at the opposite end, said plate member being selected from the same metal as said waveguide section.
